UNITED STATES PATENT OFFICE.

RILEY M. DODD, OF TORRANCE, CALIFORNIA.

HOSE CONNECTION.

Application filed April 3, 1924. Serial No. 704,031.

To all whom it may concern:

Be it known that I, RILEY M. Dodd, a citizen of the United States, residing at Torrance, in the county of Los Angeles and 5 State of California, have invented certain new and useful Improvements in Hose Connections; and I do hereby declare the following to be a full, clear, and exact description of the invention, such as will enable others 10 skilled in the art to which it appertains to make and use the same.

This invention relates to improvements in 15 couplings, and more particularly to devices of this kind through the medium of which 15 hose and nozzles are connected together.

The invention has for its primary object 20 the provision of a novel, simple and inexpensive means which, while capable of general application, shall be especially adapted 25 to connect the hose and nozzle of a mud pump against the possibility of accidental disconnection.

With the above and other objects in view, 30 the invention consists in the construction, combination and arrangement of parts hereinafter fully described and claimed, and 35 illustrated in the accompanying drawing, wherein:

Figure 1 is a sectional view taken on a 30 plane extending longitudinally through a partly assembled nozzle and hose, the former being equipped with coupling means embodying my invention,

Figure 2 is a similar view on an enlarged 35 scale, illustrating the initial step in the application of the hose to the nozzle,

Figure 3 is a similar view illustrating the 40 final step in the application of the hose to the nozzle,

Figure 4 is a transverse sectional view 45 taken on the plane indicated by the line 4-4 of Figure 3,

Figure 5 is a sectional view on an enlarged 50 scale taken on a plane extending longitudinally through one of the slips and the adjacent part of the nozzle,

Figure 6 is a detail plan view of one of 55 the slips, and

Figure 7 is a sectional view taken on the 60 plane indicated by the line 7-7 of Figure 5.

Referring to the drawing by reference numerals, 1 designates a nozzle of the kind through the medium of which a hose is connected to the mud pump of an oil well drilling apparatus of the rotary type and to which the hose 2 is secured through the

medium of a coupling embodying my invention.

In accordance with my invention one or 60 more clamps 3 of any well known construction, and slips 4 embodying a novel construction and mounted upon the nozzle 1 in a novel manner, are employed to secure the hose 2 to the nozzle 1 against the possibility of accidental disconnection therefrom. The nozzle 1 is provided with a plurality of equally spaced grooves 5 for the reception of the slips 4. The grooves 5 extend longitudinally of the nozzle 1, they are of arcuate formation in cross section, and 65 they are considerably longer than the slips 4. The bottom walls of the grooves 5 slope outwardly in the direction of the rear end of the nozzle 1. The slips 4, which are provided on their outer sides with forwardly 70 facing teeth 6, are also of arcuate formation in cross section and have a snug sliding fit in the grooves 4. Cap screws 7 which pass through slots 8 formed in and extending 75 longitudinally of the slips and which engage the nozzle 1, are employed to prevent the radial displacement of the slips 4 and to limit their longitudinal movement rearwardly with respect to the nozzle 1. The 80 slots 8 are countersunk or enlarged laterally 85 at the outer sides of the slips 4 to receive the heads of the cap screws 7.

Due to the outwardly and rearwardly sloping bottom walls of the grooves 5, the slips 4 move radially inward with respect 90 to the nozzle 1 when slid forwardly thereon and radially outward with respect to the nozzle when slid rearwardly thereon. Before applying the hose 2 to the nozzle 1, the slips 4 are moved into the deepest portions of the grooves 4, as shown in Figure 1. After the hose 2 has been applied to the nozzle 1 over slips 4, as shown in Figure 2, the clamps 3 are secured in place under sufficient pressure to cause the teeth 6 of the slips 4 to embed in the hose 2, and then the hose is moved rearwardly on the nozzle 1 into the position shown in Figure 3. During this movement of the hose 2, the slips 4 are moved into the shallower 100 portions of the grooves 5, with the result that the hose 2 will be more firmly secured between the clamps 3 and the slips 4. Owing thereto, and as the rearward movement of the slips 4 on the nozzle 1 is limited 105 by the screws 7, the hose 2 cannot become accidentally disconnected from the nozzle 1.

From the foregoing description, taken in connection with the accompanying drawing, it should be apparent that my improved coupling is simple and durable, that it is inexpensive to manufacture, and that the hose cannot become accidentally disconnected from the nozzle as any rearward movement of the hose on the nozzle, such for instance as that caused by the rearward pressure exerted against its inner side by the material being forced therethrough, would only result in a firmer connection being established between the hose and nozzle.

It should also be understood that the drawing is merely illustrative and does not pretend to give exact proportions. Furthermore, the said drawing is illustrative of a preferred construction, it being my expectation that various changes and modifications may be made without departing from the spirit and scope of my invention.

While the coupling is illustrated and described in connection with a particular type of nozzle, it is obviously capable of being used in connection with nozzles of any character and construction. It is also obviously capable of being used for the purpose of securing hose sections to couplings of that type employed to unite the sections of a fire, garden or other hose. Furthermore, it should be understood that I do not wish to limit myself to the stated manner of applying the hose to the nozzle, as it is obvious that to attain this end it is not necessary to move the hose, clamps and clips from the position shown in Figure 2 to that shown in Figure 3.

What is claimed is:—

1. A hollow member provided with a sloping surface, a toothed slip slidably po-

sitioned on said surface, and means for limiting the movement of the slip with respect to the member.

2. A hollow member provided with a groove having an outwardly sloping bottom wall, a toothed slip slidably mounted in the groove in contact with said bottom wall, and means for limiting the movement of the slip with respect to the member.

3. A hollow member provided with a longitudinally extending groove having an outwardly sloping bottom wall, a toothed slip slidably mounted in said groove and provided with a longitudinally extending slot, and a retaining element engaging the slip and member and passing through said slot.

4. A hollow member provided with a hose retaining means mounted thereon for simultaneous longitudinal and radial movements with respect thereto and means adapted to clamp the hose to said first named means.

5. A hollow member provided with sloping surfaces extending longitudinally thereof, hose retaining slips slidably mounted on said surfaces, and means adapted to clamp the hose to said slip.

6. A hollow member provided with sloping surfaces extending longitudinally thereof, toothed slips slidably mounted on said surfaces, means limiting the movement of the slips, and means adapted to clamp a hose about said slips.

In testimony whereof I affix my signature in presence of two witnesses.
